UNITED STATES PATENT OFFICE.

MARTIN F. MEEHAN, OF NEW YORK, N. Y.

DESIGN FOR A DIE FOR BUTTER-CUTTING MACHINES.

SPECIFICATION forming part of Design No. 32,488, dated April 10, 1900.

Application filed March 9, 1900. Serial No. 8,082. Term of patent 14 years.

To all whom it may concern:

Be it known that I, MARTIN F. MEEHAN, of New York, in the county of New York and State of New York, have invented a certain 5 new and original Design for Dies for Butter-Cutting Machines; and I do hereby declare the following to be a full, clear, and exact description of the invention, such as will enable others skilled in the art to which it applies to make and use the same.

In the accompanying drawings, Figures 1 and 2 are views in perspective. Fig. 3 is a central longitudinal sectional view. Fig. 4 is a transverse sectional view.

As shown in the drawings, the leading or material feature of my design consists of a plate A of approximately inverted-U shape—

that is, it has a flat top and two depending sides. The top of the plate is surrounded at one side and both ends by a flange a. Slots 20 a' are formed in this flange a and also in the top and sides of plate A. These slots extend down to near the lower or bottom edges of the sides, which edges are bent outwardly at a².

I claim as my invention—
The design for a die for butter-cutting machines, as herein shown and described.

In testimony whereof I have signed this specification in the presence of two subscribing witnesses.

MARTIN F. MEEHAN.

Witnesses:

GRAFTON L. MCGILL,
FRANK S. MAGUIRE.
